His ATTORNEYS

UNITED STATES PATENT OFFICE.

HARRY ROSENBAUM, OF NEW YORK, N. Y.

DISHWASHING APPARATUS.

Application filed November 19, 1921. Serial No. 516,418.

To all whom it may concern:

Be it known that I, HARRY ROSENBAUM, a citizen of the United States, residing at New York, county of New York, and State 5 of New York, have invented certain new and useful Improvements in Dishwashing Apparatus; and I do hereby declare the following to be a full, clear, and exact description of the invention, such as will enable others 10 skilled in the art to which it appertains to make and use the same.

This invention relates to dish washing apparatus; and it relates more particularly to dish washing apparatus of the type 15 wherein a rotatable spray device suitably mounted within a container for dishes directs a plurality of streams of water upon the dishes. A dish washer of the general type here in question is disclosed in my 20 Patent No. 1,386,734 granted August 9, 1921; and the present invention involves certain novel features of construction in the nature of improvements upon that type of construction, as well as others of more 25 general application, as will more fully hereinafter appear. Some of the principles underlying the present invention are disclosed broadly in my prior copending application, Serial No. 497,146, filed August 31, 1921, 30 of which the present application is a continuation in part.

Generally stated, the principal object of the present invention is to render still more convenient, dependable and effective in operation dish washers of the character above 35 mentioned; and especially to provide apparatus of this kind which is certain in its action and yet requires little or no skill or care to operate, and which is therefore particularly well adapted for ordinary household 40 use.

A further object is to provide a dish 45 washer construction in which the mounting of the moving parts is of such nature and arrangement that freedom of movement of such parts is always ensured even under conditions of rough handling, whereby not only is the operating power required reduced to a minimum, but also the employment of relatively light material, especially for the dish receptacle or tank, is made feasible.

Another object is to provide a construc-

tion in which the parts constituting the water-supply means and the revoluble spray 55 means can be assembled with each other and with the dish receptacle easily and quickly to give a resultant strong and sufficiently rigid construction, and can as readily be disassembled for cleaning or other purposes. 60

Still another object of the invention is to provide a spraying device that directs cleansing streams or jets against the dishes in a more thorough, systematic and effective 65 manner than has been possible heretofore in dish washing machines of this general type.

With the foregoing general objects in view, as well as some others that will be obvious as the description proceeds, the invention comprises the features, details of 70 construction and combinations of parts which will first be described in connection with an illustrative embodiment of the broad principles of the invention in an especially desirable specific construction, and 75 will then be more particularly pointed out in the appended claims.

The accompanying drawings forming a part hereof show one particularly advantageous practical form which the broad invention may take. In these drawings,

Fig. 1 is a vertical transverse section through the dish washer on the line 1—1 of Fig. 2;

Fig. 2 is a plan view of the washer with 85 the cover removed;

Fig. 3 is a central longitudinal section, or a larger scale, of the spray device and associated parts, showing details of construction and arrangement;

Fig. 4 is a transverse sectional detail on the line 4—4 of Fig. 3; and

Fig. 5 is a longitudinal section of the tubular spray device on the line 5—5 of Fig. 4.

Referring to the drawings, 10 designates generally a dish receptacle or container, closed by a removable cover 11. In the present example, the dish receptacle or tank is rectangular in shape, having two pairs of 100 opposed vertical parallel walls, 12—12 and 13—13, and a bottom 14 provided with a suitable drain outlet 15 of any suitable form and convenient location. Extending horizontally between the walls 13—13 is a tubular spray device 16, rotatably carried upon 105

stationary supporting means which serve also to rigidly connect and brace the walls 13—13, thereby preventing said walls from being warped or bent in such manner as to 5 interfere with free rotation of said spray device. As will appear more fully herein-after, said spray device is of the self-propelled reaction-jet type, so that perfect freedom of movement on its bearings is of prime 10 importance. Most desirably, and as shown in the present example, said supporting means comprises the water-supply pipe 17, perforated as indicated at 18 for flow of water into said spray device and adapted 15 to be rigidly but removably connected at its opposite ends to said walls 13—13. Such connection may be variously effected, but the construction illustrated is especially serviceable and convenient. The ends of the 20 supply tube 17 are threaded, as shown, one end screwing into a tubular fitting 19, which provides a water-supply inlet and which will be described in greater detail presently, and which has its flange 19^a tightly secured by 25 rivets 20, or otherwise, to one of said walls 13, the boss 21 of said fitting projecting a short distance inside the wall through an opening therein. On the other threaded end of tube 17 is a supporting and closure 30 member 22, in the nature of a cap nut, having a tubular portion 23 that projects through an opening 24 in that wall 13 of the receptacle a distance limited by the stop-flange 25, and screws on to said other end 35 of the supply tube 17. The tubular portion 23 of the cap or closure is externally threaded also to take a locking or clamping nut 26, by means of which the wall 13 can be firmly clamped between said clamping 40 nut and the flange 25 of the cap nut to lock the parts in place.

It will be seen that this arrangement provides for holding the opposing walls 13—13 rigidly in predetermined spaced relation, at 45 least in the location adjacent the ends of the rotatable spray tube 16. This latter, of which preferably only the apertured end walls 27, 28, bear upon the stationary supply tube, is best capable of slight longitudinal play between boss 21 and portion 23 of the cap as indicated. Obviously, even if the walls of the dish receptacle be made 50 of relatively thin sheet metal, warping and bending of the walls through careless handling or for other reasons cannot operate to bind or cramp the rotatable spray tube upon 55 its bearings, any such occurrence being precluded by the rigidity of the combined supporting and wall-spacing means described. 60 This is a consideration of the utmost importance in view of the fact that for household use a dish washer should be as light as possible so that it can be easily lifted from place to place. Another advantageous feature 65 of the combined supporting and sup-

ply tube 17 in the form here shown, where the supply pipe 17 has apertures distributed along the greater part of its length, is to supply water substantially uniformly to the spray device at all points.

Referring now to the particular form of rotatable spray illustrated, this embodies important novel features in and of itself. The tube 16, which may be of any desired cross-sectional shape, constitutes an elongated chamber, having the end walls 27 and 28 through which extends the supply pipe 17, and provided with jet apertures or devices for the discharge of liquid outwardly upon dishes in the receptacle. In the broader aspects of the invention the particular form and arrangement of these jet apertures or devices are not material; but in certain other and narrower aspects they are of considerable practical importance. 75 In the construction here shown, the rotatable tube 16 is rectangular and substantially square in cross-section. It is provided with several longitudinal series of jet apertures, there being four such series in this instance 80 designated 29, 30, 31, and 32, respectively. Although the practice of the invention does not exclude the employment of more complicated jet devices, such as projecting jet tubes or nozzles on the rotatable spray device, the simple jet apertures, consisting merely of perforations or small holes extending through the walls of the spray tube, are found to serve admirably in practice 85 and are especially recommended. Since it is desirable to utilize the reaction jet effect to rotate the spray tube, a sufficient number of the jets should discharge tangentially with respect to the rotation axis to achieve 90 this result. In the present instance, all the jets discharge tangentially, but at different 95 angles in order to more thoroughly cover the field to be sprayed. Thus, jet series 29 and 30 extend through the corresponding 100 walls of the tube perpendicularly or at right angles thereto; while series 31 and 32 extend obliquely through the other walls and hence streams of liquid discharged therethrough 105 exert somewhat less propelling effect on the tube but, on the other hand, diversify and 110 enhance the cleansing action of the spray device as a whole, especially as the obliquity 115 of these two series of jets is opposite in order to give a zig-zag or oscillating spray effect as the tube rotates. Most desirably 120 all the jets are arranged to discharge at the maximum radial distance from the axis of rotation permitted by the dimensions of the spray tube, thus securing the maximum 125 reaction effect.

In order to still further enhance the thoroughness and effectiveness with which the rotatable spray tube directs its cleansing streams to all points in the dish receptacle, it is desirable to mount the spray tube ec- 130

centrically on the supporting pipe 17; or, in other words, so that its longitudinal axis is at an angle to the axis of rotation, said axis of rotation being the axis of pipe 17.

5 In the construction illustrated, this is accomplished by locating eccentrically the apertures 27^a, 28^a, in the end walls of the spray tube, through which the pipe 17 extends. The result is very materially to increase the covering power of the spray device. This is evident from the fact that any two diametrically opposite jets of tube 16 are, by the described expedient, offset with respect to the axis of rotation a distance depending upon the angle which the spray tube axis is inclined thereto, said jets therefore traversing different rotational paths instead of the same path. Moreover, the off-center mounting has the further effect of varying the virtual radial distances of the jets in each series from the rotation axis, notwithstanding the fact that the jets may be located, as here shown, at substantially the same radial distance from the axis 25 of the spray tube.

Referring again to the tubular fitting 19, this is formed interiorly with a chamber 33 into which fits a perforated soap container 34, the container having a screw cap closure 35, as shown. The sides of the soap container are spaced away from the walls of the chamber to provide an annular passage 36 for free passage of water from the nipple 37 provided on said fitting 19 for a hot water hose connection 38. When the unitary flanged fitting 19, including the soap box and nipple, has been secured to the wall 13 of the container, it is a very simple matter to assemble therewith the other parts described. The tube 16 being held inside the receptacle with its end wall openings 27^a and 28^a in alignment with the opening in boss 21 and the opening 24 in the opposite wall of the receptacle, and clamping nut 26 being held between end wall 27 and adjacent wall 13, the pipe 17 is passed through opening 24, nut 26, and openings 27^a and 28^a successively, and screwed into the threaded channel in boss 21; after which cap 22 is screwed on to the opposite end of pipe 17 until stopped by the flange 25, the milled head 22^a rendering it easy to turn the cap with the fingers. The clamping nut 26 is then turned down tight, a gasket (not shown) being optionally used on either the inner or outer side of the wall to ensure a tight joint. It is equally easy to disassemble the parts, which is sometimes desirable in order to thoroughly clear the spray pipe of accumulated soap.

Most desirably the rotatable spray device is located centrally within the dish receptacle or tank, and the dishes and utensils to be washed are supported in proper position by means of racks or the like substantially surrounding said spray device. Thus on the floor or bottom of the receptacle are arranged racks 39 and 40 for such dishes as small plates and saucers; while at 41 are taller racks for larger plates, platters, and the like. A foraminous basket like holder 42 may be provided for spoons and cutlery. Above the spray device a foraminous tray or basket 43, which may be of wire, is removably supported as by lugs 44 resting upon a ledge 45, said lugs being secured to the rim or edge 46 of the tray. This tray is most desirably provided with an open or cut-out portion here shown as bounded by the cross-members 47, 48 and the rim 46. This allows room for large dishes such as platters and large plates 49, standing on edge in racks 41 to project above the level of the tray bottom. Properly spaced pairs of members, as indicated at 50 and 51, allow dishes such as tumblers and cups to be placed in the most advantageous positions on the tray bottom to receive streams of soapy water from the rotatable spray device.

The operation of the dish washer and its mode of use are sufficiently evident from the foregoing description. With the dishes placed in the receptacle as shown, and a small piece of soap in the container 34, connection to a hot water tap is made by means of the hose or tubing 38 and the hot water turned on. The dish washer can conveniently be set on the drain board at one end of the usual kitchen sink, with the hose connection 38 and drain outlet 14 toward the sink proper. Soapy hot water flows into the supply pipe 17 and out through the apertures 18 into the spray tube 16 which is thereby kept full. Fine jets of water emerging from the several series of jet apertures immediately set the spray device in rapid rotation, and the cleansing jets are directed against the dishes in all parts of the receptacle, the described construction and arrangement of the spray device making for exceptionally thorough and rapid cleansing of the dishes. The effectiveness of the operation is furthered by disposing at least some of the plate racks, such as 39 and 41, angularly with respect to the spray device in such a way that the plates can be supported with their upper surfaces inclined toward the spray device. The waste water passes off through discharge outlet 15 as fast as clean water is admitted to the apparatus. In actual practice it is found that the washer is very economical of hot water and that dishes treated thereby are completely cleansed in a very few minutes.

What I claim is:

1. A dish washer comprising, in combination, a walled dish receptacle, a water-supply pipe extending horizontally between

and supported by opposite walls thereof, and a spray device mounted to rotate with respect to said receptacle upon said pipe and to be supplied with liquid by said pipe.

5. 2. A dish washer as set forth in claim 1, in which said spray device is provided with reaction jets for rotating the same.

3. A dish washer comprising, in combination, a dish receptacle having two opposite 10 upright walls substantially parallel, a water-supply pipe extending horizontally between said walls and connecting the same rigidly, and a tubular spray device mounted to rotate upon said pipe and to be supplied with liquid thereby, said device bearing on said pipe at points adjacent said opposite walls.

4. A dish washer as set forth in claim 3, in which said spray device is provided with 15 reaction jets for rotating the same.

5. A dish washer comprising, in combination, a dish receptacle having opposite upright walls substantially parallel, a perforate water-supply pipe extending between 20 said walls, a tubular spray device mounted to rotate on said pipe and to be supplied with water thereby, said device being provided with reaction jets for rotating the same and spacing means rigid with said 25 pipe adjacent said opposite walls spacing said tubular spray device from said opposite walls.

6. A dish washer comprising, in combination, a walled dish receptacle, a tubular 30 liquid-inlet or supply member mounted on a wall of said receptacle and opening into said receptacle, a laterally apertured pipe detachably secured at one end to said inlet member to receive liquid therefrom, means 35 securing the other end of said pipe to an opposite wall of the receptacle, and a tubular spray device, rotatable on said apertured pipe and substantially coextensive therewith, said device being provided with 40 jets of which at least a part discharge tangentially with respect to said pipe.

7. A dish washer comprising, in combination, a walled dish receptacle, a tubular liquid-inlet or supply member mounted on 45 a wall of said receptacle and opening into said receptacle, a laterally apertured pipe having a threaded connection at one end to said inlet member, a closure device threaded on the other end of said pipe and securing 50 it to an opposite wall of said receptacle, means clamping said closure device against such wall, and a tubular spray device substantially enclosing said pipe and rotatable thereon, said device being provided with 55 jets of which a part discharge tangentially with respect to said pipe.

8. A dish washer comprising in combination, a stationary dish receptacle having a 60 pair of substantially parallel walls, a member extending between and maintaining said

walls a predetermined distance apart, and a tubular spray device substantially enclosing said member and rotatable thereon.

9. A dish washer comprising, in combination, a dish receptacle having a pair of substantially parallel walls, a member extending between and maintaining said walls a predetermined distance apart, and a tubular spray device substantially enclosing said member and rotatable thereon, said spray device including reaction jet means for rotating the same. 70

10. A dish washer comprising, in combination, a dish receptacle, and an elongated spray device mounted within said receptacle to rotate upon an axis disposed at an acute angle with respect to the central longitudinal axis of said device. 75

11. A dish washer comprising, in combination, a dish receptacle, and an elongated tubular spray device provided with a plurality of series of jets along its length and mounted within said receptacle to rotate upon an axis slightly inclined with respect to the central longitudinal axis of said device, a substantial proportion of said jets being arranged to discharge tangentially with respect to the axis of revolution and thereby to act as reaction jets to rotate said tubular spray device. 85

12. A dish washer as set forth in claim 11, wherein the jets are arranged to discharge at different angles. 90

13. In washer apparatus, the combination, 100 with a tubular fitting, of a laterally apertured pipe having a threaded connection at one end to said fitting, a closure member having a threaded connection to the other end of said pipe, and a spray tube rotatably mounted on said pipe and confined between 105 said tubular fitting and said closure member.

14. Apparatus as set forth in claim 13, wherein said tubular fitting includes a soap holder and means providing a connection to a water supply. 110

15. In washing apparatus, a spray device comprising a rotatably mounted tubular chamber polygonal in cross-section having a plurality of series of jets, one series 115 for each face, extending longitudinally of said chamber and discharging tangentially with respect to the axis of rotation, said series of jets cooperating to rotate said spray device. 120

16. A washer apparatus comprising, in combination, a walled receptacle adapted to receive articles to be cleansed, a tubular fitting mounted in a wall of said receptacle, a laterally apertured pipe having a threaded connection at one end to said fitting to extend into said receptacle, a closure member having a threaded connection to the other end of said pipe, and a spray tube rotatably mounted on said pipe and confined between 125 130

said tubular fitting and said closure member.

17. A washer apparatus comprising, in combination, a walled receptacle adapted to receive articles to be cleansed, a spray device in said receptacle comprising a rotatably mounted tubular chamber polygonal in cross-section having a plurality of series of jets, one series for each face, extending

longitudinally of said chamber and discharging tangentially with respect to the axis of rotation, said series of jets cooperating to rotate said spray device.

In testimony whereof I hereunto affix my signature.

HARRY ROSENBAUM.
